FENDER LAMP

Howard C. Mead, Anderson, Ind., assignor to General Motors Corporation, Detroit, Mich., a corporation of Delaware

Application November 11, 1935, Serial No. 49,171

4 Claims. (Cl. 240—8.1)

The present invention relates to illuminating apparatus and more specifically to accessory fender lamps for use on automotive vehicles.

The principal object of this invention is to provide a fender lamp of pleasing appearance which is practical and easily serviced.

Further objects of my invention will become evident from the following specification which sets forth the embodiments of my invention as 10 illustrated in the accompanying drawings, in which:

Fig. 1 is a vertical longitudinal section through a fender lamp of my invention.

Fig. 2 is a top plan view of my invention, parts 15 being broken away and shown in section.

Figs. 3 and 4 are perspective views of the two main parts of the lamp frame.

Fig. 5 is a sectional view taken on line 5—5 of Fig. 2.

Fig. 6 is a reduced longitudinal section through the forward portion of a modified form of my invention.

The fender lamp of my invention is composed of a base frame member designated generally at 25 2, whose horizontal cross section is generally that of an ellipse with one end being smaller than the other and drawn more to a point. The lower surface of the base is curved to match the surface to which it is to be attached, namely the 30 upper surface of a fender, and the upper plain horizontal surface is flat, the forward portion 4 being slightly lower than the rearward portion 6. Extending horizontally across from one side to another are two cross frame braces 8 and 10.

35 Fitting on top of the base portion is a thin skeleton frame 12 of the same outline as the horizontal cross section of the base and fitting snugly above the latter. The frame 12 engages the upper surface of the base and in normal position is spaced from an upwardly extended flange 14 on the forward portion of the section 4 to perform a clamping action as will later be evident. Extending across from one side of the frame 12 to another there are a plurality of brackets 16, 40 18, and 20. The brackets 16 and 18 lie in the general plane of frame 12 and the bracket 20 is humped up at its center to form a wishbone 45 the purpose of which will later be clearly understood.

50 Cast within the cross member 10 of the base 2 is a securing bolt 22 and also cast within the front portion of the base 2 is a similar securing bolt 24 both of which are utilized to secure the fender lamp assembly to the fender. Extending rearwardly in the forward portion and cast integral

with the base 2 is an angled member 26 to which is secured, by suitable screws 32 in its horizontal portion, a socket member 28 into which a light bulb 30 may be screwed. Also secured by the screws 32 and between the socket 28 and the member 26 is a suitable strip of insulating material 34 which carries a contact member 36 to which the source of current may be attached. A spring contact member 38 is clamped under the inner end of the contact member 36 and has its 10 other end portion bearing against the inwardly projecting contact on the bulb base. A further disk shaped insulating member 40 surrounds the inner end of the contact 36 to space the same from the opening in the angled member 26 15 through which the contact 36 projects. It will thus be evident that all portions carrying electric current to the bulb are insulated from the base.

The inner end of the member 26 extends vertically and the top thereof forms the cross member 8 of the base 2. Secured to the cross member 10 by a machine screw 42 is an angled spring member 44 the latter being utilized to secure the outline frame 12 to the base 2. In assembling 25 these two parts it should be noted that the rear portion of the frame 12 is filled in to form a flat portion 46 the forward portion of which is pressed out to form an inclined plane 48 and when the frame 12 is placed upon the base 2 30 and drawn to its proper position forwardly the end of the spring member 44 rides upwardly on the inclined plane 48 to hold the frame 12 down securely against the base. When it has reached this position a long bolt 50 is placed through an 35 opening provided in the top of the wishbone bracket 20 and extends down through a threaded opening in the cross member 8 to lock the frame 12 in its proper position.

40 Enclosing the top of the lamp frame in a bulbous form there are provided two portions. A sheet metal stamping 52 extends rearwardly from the wishbone 20 and has a flanged lip 54 extended under the edge of the wishbone, the sides being bolted down to fit within a rim groove 45 56 on the frame member 12. Secured within this bulbous member 52 and welded to the inner side thereof are two securing brackets 58 and 60. Both of these securing members have a horizontal extension 62 which is threaded to receive 50 one end of a securing screw 64 which extends through both the cross member 10 at the forward portion and the plate 46 at the rearward portion.

Forwardly from the wishbone 20 is a bulbous 55

lens structure 66 over the top of the light bulb 30. The lower edge of the lens, which is formed in conformity with the outline of the frame 12, is flanged as at 68 and extends within a groove 5 70. Also the base 2 carries on its upper surface a resilient gasket 69 upon which the lower face of the lens rests to prevent breakage thereof and to seal the bulb compartment against dirt and water. The rearward portion of the lens 66 is 10 flanged in a vertical plane as at 72 and extends against a resilient packing means 74 which is held within the wishbone 20. The lens is therefore clamped in place between the base 2 and the frame 12.

15 In disassembling this lamp it is of course only necessary to remove the bolt 50 and slide the frame assembly to the rear to disengage spring 44 from the inclined surface and then lift the assembly clear of the base which is substantially 20 splitting the lamp structure upon its horizontal center line. The bulb may then be replaced and the frame structure again applied thereto.

In the modified form of my invention shown in Fig. 6, the base 2' has been modified by the 25 addition of a vertical leg 80 and has as before the angled member 26. Extending rearwardly from the upper end of the member 26 is a tab 82 in which there are two threaded openings 84. Fitting in the forward compartment, which is 30 triangular in horizontal cross section as in the former type, there is a triangular boat shaped cup 86. This member is secured in place by a screw 88 which threads into the top of the leg 80 and by an integral tongue 90 which extends 35 back over the top of the member 26 and is secured by a screw 92 engaging the rearmost opening 84.

In the central portion of the member 86 is a 40 flanged opening 94 adapted to support a bulb 38. Supported by the lower portion of the angle bracket 26 is a spring contact 38 as before which is adapted to press against the central contact of the bulb, the contact being insulated from the base by pads 96 and secured by riveting one end 45 of a contact 98. A similar lens 100 is supported above the bulb by the upper frame 102 and separated from the base by a cork gasket 104 to seal the joint.

50 In this form the method of attaching the forward end of the shell to the upper frame 102 is also different from the previously described type. The cross member 106 on the upper frame has a cup shaped portion 108 integral therewith 55 which seats and guides one end of a spring 108

the other end of which bears against the inside of the shell 52 the forward lip 54 of which engages under the member 20 to keep the two parts from separating and the spring keeps the assembly tight, the rear end of the shell being 5 secured as before.

The construction of this modified form is otherwise the same as previously described and so it has not been deemed necessary to show the whole or to carry the description further. The 10 changes also do not affect the assembling and disassembling methods originally described.

I claim:

1. In a fender lamp, a streamline base, lighting means secured in the base, a frame member having the same outline as the top of the base and adapted to be secured thereto, a flanged edge on the front of the frame member, a lens in the shape of one half of a modified cone, a flange on the lower edge of the lens to fit under the frame flange for securing of the same over the lighting means, and enclosing means secured to the rear of the frame and forming with the frame, base and lens a streamline structure. 15

2. In a fender lamp, a streamline base, lighting means secured in the base, a frame member having the same outline as the top of the base and having a flanged edge at the front thereof, a lens in the shape of one-half of a modified cone 20 having a flange adapted to fit under the flange 25 on the frame for securing the same over the lighting means, means for securing the base and frame members together including resilient means and threaded means and means enclosing 30 the rear portion of the frame to form with the lens, frame and base a streamline structure. 35

3. In a fender lamp, a streamline base, lighting means carried by the base and forming therewith one unit, a subframe, a lens and a bulbous member, both carried by the subframe to form a second unit, resilient means connecting one end 40 of the two units together and threaded means for connecting the other ends.

4. In a fender lamp, a streamline base, lighting means carried by the base and forming therewith one unit, a subframe, a lens and a bulbous member, both carried by the subframe to form a second unit, a spring clip carried by the base 45 to overlie a portion of the subframe in assembled 50 position to hold the two in juxtaposition and a bolt securing the opposite end of the subframe to the base.

HOWARD C. MEAD.
